FIG. 1 is a top view of a roof vent assembly; FIG. 2 is a bottom view of the roof vent assembly of FIG. 1; FIG. 3 is a front view of the roof vent assembly of FIG. 1; FIG. 4 is a rear view of the roof vent assembly of FIG. 1; FIG. 5 is a left side view of the roof vent assembly of FIG. 1, with the right side view being a mirror image of FIG. 5; FIG. 6 is a left side view of the roof vent assembly of FIG. 1 showing a lower vent member laterally displaced relative to an upper vent member, with the right side view being a mirror image of FIG. 6;

FIG. 7 is a top exploded perspective view of the roof vent assembly of FIG. 1 showing a lower vent member with an integrated fan;

FIG. 8 is a top exploded perspective view of the roof vent assembly of FIG. 1 with a solar panel, and a lower vent member with an integrated fan and an upper fan screen; FIG. 9 is a bottom exploded perspective view of the roof vent assembly of FIG. 1 showing a lower vent member with an integrated fan; and,

FIG. 10 is a bottom exploded perspective view of the roof vent assembly of FIG. 1 showing a lower vent member with an integrated fan and a lower fan screen.

DESCRIPTION
